DIAMOND-HOLDING TOOL

Julius Dinhofer, New York, N. Y.

Application May 20, 1941, Serial No. 394,275

1 Claim. (Cl. 125—39)

This invention relates to diamond-holding tools of the character employed for grinding wheel dressing purposes and for other uses, examples of such tools being shown in my co-pending applications, Serial Nos. 391,235 and 392,197.

At the present time, diamonds used for grinding or dressing purposes are usually of irregular shape and because of this are mounted with difficulty in holders in which it is necessary for them to be securely held during the hard use to which tools of this character are put.

In my co-pending applications above mentioned, it is proposed that the diamonds be first ground to a regular form, or octahedral, to enable them to be securely gripped in a specially designed holder. This requires considerable grinding which adds to the cost of production.

The present invention is intended to reduce the amount of grinding on the diamond, and simplify the holder in which the same is mounted so that a relatively inexpensive but thoroughly practical tool is produced. More particularly, the invention contemplates the provision of a diamond ground to provide two substantially conical pointed ends, and a holder in which one of said ends is seated, said holder being provided with a cap, apertured to permit the projection of the second pointed end, and acting to securely clamp the diamond on the seat and hold it against displacement.

In the accompanying drawing, wherein an embodiment of the invention is shown, Fig. 1 is a sectional view of a diamond-holding tool constructed in accordance with the invention; Fig. 2 is a side elevation of the same; Fig. 3 is a side view of one end of the tool, with the cap thereof removed and shown in section; and Fig. 4 is a plan view of the tool.

The diamond for use in the tool is prepared by a relatively small amount of grinding in order to enable the same to be securely gripped and held against displacement during the hard use to which a tool of this character is subjected. I find it desirable to grind the unfinished or rough diamond into the shape shown in Fig. 1 wherein it will be seen that the same is provided with two substantially similar pointed ends 1 and 2, each of said ends constituting the termination of a substantially cone shaped portion 3, 4. It will be understood that accurate and lengthy grinding of the diamond is not necessary, it being merely desirable that the diamond shall have two usable pointed ends and adjacent substantially conical portions for engagement by parts

of the holder as will be hereinafter pointed out.

The holder includes a rod or stem portion 5 provided with a knurled portion 6, a threaded portion 7 and a head 8. The head is formed with a recess 9, the same constituting a shallow depression of substantially circular shape, the marginal edge 10 of said recess constituting a seat for the diamond. It is desirable, although not absolutely necessary that the recess 10 shall be of less diameter than the widest diameter of the diamond. If the diamond employed is of larger diameter than the recess 10 it will have its lower cone-shaped portion 4 seated upon the edge of the recess. If it is of larger diameter, the lower pointed end can rest against the bottom of the recess 10.

The means for holding the diamond in the holder comprises a clamping member or cap 11 which is knurled at 15 and internally threaded 20 as at 12 for adjustable reception upon the threaded portion 7 of the holder. The cap has an inclined end wall 13 formed with a central circular opening 14 of a diameter less than the widest diameter of the diamond. When the cap 25 is in position, it will be seen that one of the conical ends of the diamond, namely, that shown at 3, will protrude through the opening 14 so that the point 1 of the diamond will project beyond the end wall 9 of the cap and be available 30 for use against a grinding wheel or for any other purpose. The end wall 13 of the cap is tapered and is made relatively thin adjacent to the central opening so that when the cap is tightened down, the thin and slightly elastic 35 edge of the opening 14 will be forced tightly against the conical surface of the cone-shaped portion 3 of the diamond so that the diamond will not only become wedged in the opening 14 and held against rotative movement, but 40 will also be firmly held against the seat 10 or in the recess around which said seat extends.

When the projecting end 1 of the diamond becomes worn after considerable use, the cap 11 is removed, and when this is done, the diamond, being wedged in opening 14, is usually lifted off the holder with the cap. The knurling 6 and 45 15 on the holder and cap 11, respectively, aids in permitting the cap to be unthreaded. The diamond is pushed out of the opening 14 and then placed in the seat 10 in reversed position, or with its pointed end exposed through the opening 14. The cap is then tightened down and the tool is again ready for use.

With the tool of the character described, the diamond may be prepared with a minimum of

grinding; the tool consists of only two parts, exclusive of the diamond, and will last indefinitely since a new diamond can be replaced in it whenever necessary. Also, since the diamond can be reversed when one of the pointed ends becomes worn, the tool need never leave the possession of its user.

What I claim is:

In a tool of the character described, a diamond having two substantially coned ends, each end terminating in a point, a holder having a recess in its end in which one of the coned ends of the diamond seats, a cap adjustable on said holder, said cap having a conical and integral

end wall formed with a centrally located circular opening through which the second coned end of the diamond extends, said conical end wall tapering in thickness from its outer marginal edge toward the marginal edge of the circular opening and the edge of said wall around said opening terminating in a continuous thin and substantially knife edge, the thin portion of said end wall around said opening being sufficiently resilient to permit the coned portion of the diamond extending through said opening to be wedged therein when the cap is tightened on the holder.

JULIUS DINHOFER.
